(57) **CLAIM**

The ornamental design for a display screen with graphical user interface, as shown and described.

DESCRIPTION

The sole FIGURE is a front view of a display screen with graphical user interface showing the new design.

The outermost broken lines showing an electronic device illustrate environmental subject matter and form no part of the claimed design. The dot-dash broken lines showing the outer edge of the display screen form no part of the claimed design. The remaining evenly spaced broken lines within the dot-dash broken lines show portions of the graphical user interface and form no part of the claimed design.
